UNITED STATES PATENT OFFICE

140,738

DESIGN FOR A JEWELRY CROSS

Seth Minasian, Providence, R. I.

Application November 19, 1943, Serial No. 111,731

Term of patent 3½ years

(Cl. D45—15)

To all whom it may concern:

Be it known that I, Seth Minasian, a citizen of the United States, residing at Providence, in the county of Providence and State of Rhode Island, have invented a new, original, and ornamental Design for a Jewelry Cross, of which the following is a specification, reference being had to the accompanying drawing, constituting a part thereof.

Fig. 1 is a front elevation of a jewelry cross showing my new design;

Fig. 2 is a side view thereof;

I claim:

The design for a jewelry cross, substantially as shown.

SETH MINASIAN.
